UNITED STATES PATENT OFFICE.

PLEASANT FOREST MANNING, OF OKLAHOMA, OKLAHOMA.

DOOR-LOCK.

1,079,138.

Specification of Letters Patent.

Patented Nov. 18, 1913.

Application filed June 5, 1913. Serial No. 771,871.

To all whom it may concern:

Be it known that I, PLEASANT FOREST MANNING, a citizen of the United States, and a resident of Oklahoma city, in the county of Oklahoma and State of Oklahoma, have invented certain new and useful Improvements in Door-Locks, of which the following is a specification.

My invention relates to improvements in door locks and it consists in the combinations, constructions and arrangements herein described and claimed.

An object of my invention is to reduce the trouble and expense in fitting a lock in a door by providing a lock which may be inserted in a cylindrical opening made by an ordinary brace and bit without the necessity of mortising the door.

A further object of my invention is to reduce the number of parts and to lessen the cost of manufacture of a good substantial lock.

Other objects and advantages will appear in the following specification and the novel features of the invention will be particularly pointed out in the appended claims.

My invention is illustrated in the accompanying drawings, which form a part of this application, in which similar reference characters indicate like parts in the several views, and in which—

Figure 1 is a horizontal section through the device as applied to a door. Fig. 2 is an end view of the tumbler. Figs. 3 and 3^a are side views of the tumbler. Fig. 4 is a section along the line 4—4 of Fig. 1. Fig. 5 is a section along the line 5—5 of Fig. 1, looking in the direction of the arrows. Fig. 6 is a section along the line 6—6 of Fig. 1 looking in the direction of the arrows. Fig. 7 is a sectional view on the line 7—7 of Fig. 1. Fig. 8 is a perspective view showing the assemblage of the locking stem. Fig. 9 is a perspective view of the latch.

In carrying out my invention, I provide door knobs of the form shown in Fig. 1. The head 1 of the knob is hollow and is provided with an inwardly extending lug 2 provided with a cylindrical recess arrangement to receive the key cylinder 3. This is provided with grooves 4 and is designed to fit tightly in the recess 3. The cylinder is provided with a central slot arranged to

receive the key 5. The cylindrical extension 6 of the knob is recessed at 6^x to provide means for locking the knob in place as will be explained later.

In Fig. 8, I have shown a stem 7 which is provided with an elongated segmental gear 8. The stem has a reduced squared portion 7^x at each end arranged to enter a cylindrical rod 9 having an enlarged portion 10, provided with a head 11. The head 11 is provided with a slot 11^x arranged to receive the end of the key 5. The portion 9 is provided with a locking lug 9^x. The cylindrical latch casing consists of two parts 12, see Fig. 7, which are held together at the outer ends by means of the threaded cylindrical portion 13^x of the latch plate 13, the ends of the cylindrical latch casing members being threaded for that purpose as shown in Figs. 1, 5 and 6.

Arranged to slide within the latch casing 12 is the latch which I have denoted in general by 14. It consists of a U-shaped body portion having a beveled end 14^x and a yoke 14^y extending rearwardly from the body portion. The yoke 14^y is provided with a pair of bearing shoulders 14^z (see Fig. 9) and with a second pair of bearing shoulders 14^{z2} whose purpose will be explained later.

Pivots mounted on one of the casing members 12 at the rear end thereof is a locking dog 15. This dog is provided with a series of teeth 15^z arranged to engage the teeth of the gear 8 which is carried by the stem 7. The dog 15 is held in frictional engagement with the wall of the casing 12 by means of a spring 16 (see Fig. 1) which surrounds a portion of the pivotal bearing 15^x of the dog, and which bears at its opposite end on the other casing member. The dog is provided with a shoulder 15^y arranged to engage the rear end of one of the arms of the yoke 14^y.

At 17 I have shown the squared door knob shank which is designed to enter the squared openings in the members 6. One corner of the shank has a semicylindrical groove arranged to receive the cylindrical members 7 and 9 of the locking stem. As will be seen from Fig. 4, this shank is provided with a recess 17^a arranged to receive the projecting portion of the lug 9^x. When the latter

UNITED STATES PATENT OFFICE.

JAMES L. O'NEILL, OF MACEDON, NEW YORK.

AGRICULTURAL MACHINE.

1,079,139.

Specification of Letters Patent.

Patented Nov. 18, 1913.

Application filed February 3, 1913. Serial No. 746,010.

To all whom it may concern:

Be it known that I, JAMES L. O'NEILL, a citizen of the United States, and resident of Macedon, in the county of Wayne and State 5 of New York, have invented new and useful Improvements in Agricultural Machines, of which the following is a specification.

This invention relates to agricultural machines, such as machines for digging potatoes and the like, in which beater-mechanism is employed for the purpose of separating the adherent earth from plants dug or raised by the machine, or for separating potatoes or other tubers from the vines. In machines 10 of the type in question it is common to employ beaters, or combined conveying and separating devices, comprising bars, fingers and the like which are actuated in such a manner as to agitate the material supported 15 and carried thereby to promote the separation of the earth from the plants, or of the tubers from the vines upon which they grow. It has also been proposed to employ mechanism 20 for this purpose in the form of a series 25 of parallel rotatable supports or shafts provided with longitudinal rows of fingers, the supports being rotated in unison in the same direction, whereby the material discharged upon the first fingers is conveyed from one 30 row to another, the fingers thus constituting means for both supporting and agitating the material. In such previously-proposed constructions, however, the fingers are so 35 formed, and arranged to coöperate in such a manner, that they tend upon their supports to pinch the material between them, with the result that the apparatus becomes clogged.

The object of the present invention is to 40 provide beater-mechanism, for an agricultural machine, consisting of a series of rotating supports having longitudinal rows of fingers, the fingers being so formed and arranged as to be free from the objection just 45 pointed out and to transfer the material readily and freely from one row of fingers to another. To this end I form the fingers, and mount them upon their supports, in such a manner that the major portion of 50 each finger extends in a direction tangential to a circle concentric with the support, but of greater diameter, this major portion projecting also in a direction contrary to the direction of rotation of the support. Fur- 55 thermore, the tangential parts of the fingers

of each row, when they assume the upright position in which they discharge the material supported by them upon a row of fingers on the next rotating support, are substantially at right angles to the tangential portions 60 of the latter row of fingers, while the extremities of the latter row of fingers extend to, and pass upwardly between, the tangential portions of the fingers of the first-mentioned row, and thus the material is 65 stripped cleanly from the first row of fingers without any danger of being pinched between the fingers, while the fingers constitute the sole means for supporting and conveying the material. While the advantages 70 of this arrangement can be secured to some extent in an arrangement in which the fingers on one only of two adjacent supports are arranged in the peculiar manner which I have described, the invention, in its fullest 75 embodiment, comprises a plurality of parallel rotating supports, each provided with fingers formed and mounted thereon in the novel manner in question.

In the accompanying drawings:—Figure 80 1 is a side-elevation of a potato-digger embodying the present invention, with the nearer parts removed by a section on the line 1—1 in Fig. 2; Fig. 2 is a plan-view of the machine of Fig. 1, with the uppermost 85 parts removed by a section on the line 2—2 in Fig. 1; and Fig. 3 is a detail-view, in vertical transverse section, of one of the rotatable supports, together with the fingers carried thereby. 90

The invention is illustrated as embodied in a machine for digging potatoes and the like, this machine having supporting- and traction-wheels 5 which support the other parts of the machine and also furnish power, 95 in the usual manner, for actuating its moving parts. A main frame 6 is supported by the wheels, this frame being provided with any suitable draft-device, such as a pole 7, by which it may be drawn over the ground 100 by horses or otherwise. At the front of the machine is a plow or shovel 8 of ordinary form which, in the operation of the machine, is drawn through the ground at a suitable depth to dig or raise earth together with the potato-vines or other plants upon which the machine is to act, as shown in Fig. 1. The beater-mechanism is located in the rear 105 of the plow, and is adapted to receive the earth and plants therefrom and to separate 110

the earth from the plants, finally discharging the plants at the rear of the machine.

The plow 8 is shown as fixed to a cross-bar 9 which constitutes a portion of a sub-frame having inclined parallel side-members

5 10 and a yoke-shaped rear transverse member 11. This sub-frame provides also the support for the beater-mechanism. As shown in Fig. 1, each side-member 10 provides bearings for a series of trunnions 12, 13, 14, 15 and 16 by which a series of transverse cylindrical supports 17 to 21 are journaled on the sub-frame. Each of these supports, as shown particularly in Fig. 3, is 10 provided with four longitudinal rows of fingers 22 fixed rigidly to the support at their inner ends. From the rear-edge of the plow 8 another series of fingers 23 projects upwardly and rearwardly, and the fingers 22 15 on the foremost support 17 pass between the fingers 23 in an upward direction when the support is rotated during the operation of the machine, so that the material raised by the plow is picked up and carried rearwardly, in detached portions, by the fingers 22 on the support 17, and from them it is 20 then passed backwardly to the fingers on the support 18, and so on until it reaches, and is discharged from, the fingers on the rear-most support 21.

As shown particularly in Fig. 3, each of the fingers 22 has a short portion 25, adjacent the support, which is radial with respect to the latter. The finger is then bent 25 sharply at a point 26, so that the major portion of the finger lies in a line tangent to a circle concentric with the support, but of substantially greater diameter. The supports are placed only so far apart as is necessary to permit the ends of the fingers 30 to pass freely by the adjacent supports, and owing to this arrangement, and to the form of the fingers, it results, as shown in Fig. 1, that when any row of fingers upon 35 one of the supports reaches a position in which it may discharge the material supported by the fingers upon a row of fingers on the next succeeding support, the two rows of fingers meet and slightly overlap in a 40 position in which they are at right-angles to each other, and accordingly the material may be transferred cleanly from one row of fingers to the next without any tendency to cramp between the fingers. Thus the material 45 passes rearwardly from the foremost fingers to the rearmost fingers, and at the same time it is subjected to a continuous agitation which effectually shakes the earth away from the vines, the earth falling freely, 50 between the fingers, upon the surface of the ground, while the vines are carried rearwardly.

As shown in Fig. 2, the rearmost frame is provided with only half as many fingers as 55 the other supports. In this manner wider

spaces are provided through which potatoes, or other tubers, may be shaken from the vines, while the vines are carried to, and discharged from, the rear side of the rearmost support.

The means for rotating the supports simultaneously in the same direction comprise sprocket-wheels 24 fixed on the trunnions 12 to 16, inclusive. The sprocket-wheels on the trunnions 12 to 15, inclusive, are connected 70 by sprocket-chains 27, while the trunnions 15 and 16 are connected by sprocket-chains 28. The trunnions 15 are thus connected with the several supports so that they may act as common driving-members for these 75 supports. To this end each trunnion 15 has a squared extremity upon which is slidably mounted a toothed clutch-member 29. This clutch-member co-operates with a toothed clutch-member 30 which is journaled coaxially with the member 29. A bearing for each clutch-member 30 is provided by a yoke-shaped lateral extension 31 at each side of the sub-frame, this member having a bearing-boss 32 projecting inwardly into a central recess in the clutch-member 30. Each clutch-member 30 is integral with a pinion 33 which meshes with a driving-gear 34. Each gear 34 has an integral hub or sleeve 35 to which one of the wheels 5 is secured by 80 a set-screw 36, so that the gear 34 is rotated by the corresponding wheel. To support the sub-frame firmly upon the wheels, and maintain the several rotative parts in proper 85 operative position, a stub-shaft 37 projects, from each side-member 10 of the sub-frame, through the hub 35 of the corresponding gear 34, and is provided, at its outer end, with a head 38 which retains the hub upon the shaft. The hub 35 serves also as the 90 immediate support for the main frame 6 of the machine, this frame having a bearing-boss 39 surrounding the hub, as shown in section in Fig. 2.

By the mechanism just described the supports 17 to 21, together with the fingers thereon, are all rotated in the counter-clockwise direction indicated by arrows in Figs. 1 and 3, and at the same speed, by power derived from the traction-wheels 5.

In order that the plow may be raised from engagement with the ground when the machine is to be drawn idly from place to place, and for the purpose of simultaneously throwing the beater-mechanism out of operation, a hand-lever 40 is pivoted at 41 upon the main-frame 6 of the machine, and the forward end of this lever is connected, by a link 42, with a point on the sub-frame in advance of its axis of pivotal movement 120 upon the hubs 35. By depressing the hand-lever 40 the sub-frame may be swung in a direction to raise the plow from the ground. A toothed sector 43 is mounted on the main frame 6 in a position to co-operate with the 125

hand-lever so as to hold the parts in adjusted position, the lever being maintained in engagement with the sector by its resiliency, and being disengaged therefrom by bending it laterally when necessary. This arrangement also permits the adjustment, at will, of the depth to which the plow enters the ground, and consequently of the amount of material removed by the plow.

10 In order that the movement of the hand-lever, by which the plow is raised, may also interrupt the actuation of the beater-mechanism, the tilting movement of the sub-frame is utilized to throw the driving-clutches above described out of operation. Each of the clutch-members 29 has an annular groove which is engaged by one arm 44 of a bell-crank lever pivoted on one of the yoke-shaped members 31 on the sub-frame. The other arm 45 of the bell-crank lever carries a roller 46 which is adapted to coöperate with a cam-member 47 fixed at the rear end of the main frame 6. A coiled spring 48, connected with the bell-crank lever, normally maintains the lever in a position to hold the clutch-members in operative engagement, but when the sub-frame is tilted by the hand-lever sufficiently to raise the plow from the ground the bell-crank levers are thus swung downwardly into a position in which the rollers 46 engage and are pressed forwardly by the cam-members 47, which results in swinging the arms 44 of the bell-crank levers inwardly, thus sliding the clutch-members 29 out of coöoperative engagement with the clutch-members 30 and disconnecting the beater-mechanism from the traction-wheels 5.

To maintain the sprocket-chain 27 firmly in engagement with the sprocket-wheels 24 idler-wheels 50 are journaled upon the side-members 10 of the sub-frame, in position to engage each of the upper stretches of the chains 27 between their points of engagement with adjacent sprockets. The side-members 10 also support mold-boards or side-walls 51 which confine the earth and the vines laterally upon the plow and the beater-mechanism.

50 My invention is not limited to the embodiment thereof hereinbefore described and illustrated in the accompanying drawings, but it may be embodied in various other forms within the nature of the invention as 55 it is defined in the following claims.

I claim:—

1. In a machine for digging potatoes and the like, mechanism for conveying and separating earth and vines, said mechanism comprising a series of parallel rotatable supports provided with uniformly-spaced rows of fingers, each finger having its major portion tangential to a circle concentric with, but of greater diameter than, the support and projecting opposite to the direction of rotation of the support, and the fingers in each row being long enough to extend to and between the tangential portions of the fingers of a row on the next support when the tangential portions of the two rows of fingers are at right-angles to each other, and means for rotating the supports at uniform speeds; the spaces between the fingers and above the supports being free and unobstructed so that the fingers constitute the sole means for supporting the material during the beating and transferring operation.

2. In a machine for digging potatoes and the like, mechanism for conveying and separating earth, vines and tubers, said mechanism comprising a series of parallel rotatable supports provided with uniformly-spaced rows of fingers, each finger having its major portion tangential to a circle concentric with, but of greater diameter than, the support and projecting opposite to the direction of rotation of the support, and the fingers in each row being long enough to extend to and between the tangential portions of the fingers of a row on the next support when the tangential portions of the two rows of fingers are at right-angles to each other, and means for rotating the supports at uniform speeds and in the same direction, the spaces between the fingers and above the supports being free and unobstructed so that the fingers constitute the sole means for supporting the material during the beating and transferring operation, and the fingers on the rearmost support being arranged at distances twice as great as those on the other supports, so as to provide wider intervening spaces through which tubers may be dropped, while the vines are supported by the fingers and discharged in the rear of the rearmost support.

JAMES L. O'NEILL.
